UNITED STATES PATENT OFFICE.

ALBERT S. NEWBY, OF KANSAS CITY, MISSOURI.

DESIGN FOR A GRATE.

SPECIFICATION forming part of Design No. 26,494, dated January 5, 1897.

Application filed October 6, 1896. Serial No. 608,067. Term of patent 14 years.

To all whom it may concern:

Be it known that I, ALBERT S. NEWBY, a citizen of the United States, residing at Kansas City, in the county of Jackson and State of Missouri, have invented a certain new and original Design for Bottom Grates for Heating-Stoves; and I do hereby declare the following to be a full, clear, and close description thereof.

My invention comprises certain novel and original elements for a design for bottom grates for heating-stoves; and it essentially consists in a rim with grooves therein, a second rim of smaller diameter hung below the first rim, and the two rims united by bars with a circular grate pivoted upon the lower rim, all of which will be fully set out and described in the following specification and illustrated in the accompanying drawings, which form a part hereof.

Figure 1 is a plan view of my design. Fig. 2 is a cross-section through line X X of Fig. 1.

In the drawings the upper rim is represented by A. Near the center of the rim A there is a groove *a*, forming a complete circle 25 in the surface of the rim. From the groove *a* there are other grooves, *b*, running perpendicular from the groove *a* to the outer edge of the rim A. Below the rim A is another rim, B, which is united to the rim A by bars 30 *d*, and upon the rim B rests the grate D. The grate D consists of a ring *e* with bars *f*, stop *g*, pivot-pins *i*, and handle E.

What I claim is--

The design for bottom grates as described 35 and shown in the drawings.

In testimony whereof I affix my signature in presence of two witnesses.

ALBERT S. NEWBY.

Witnesses:

B. F. PURSEL,
B. HOWARD SMITH.
